ELECTRICAL SHAVER

Ralph D. S. Hagopian, Berkeley, Calif.

Application July 20, 1938, Serial No. 220,233

5 Claims. (Cl. 30—43)

This invention relates generally to electrical shaver devices such as are adapted for latherless shaving.

Electrical shaving devices such as now available upon the market vary widely as to details of construction, but they universally make use of an electric motor housed within a handle, and which drives a cutter relative to a blade member. The blade member is adapted to contact the skin and is provided with a plurality of openings, such as slots or apertures, through which hair is received to be severed by the cutter. The type of drive afforded between the cutter and the motor varies in accordance with the motion imparted to the cutter. For example the cutter is rocked, oscillated, reciprocated, or directly and continuously rotated.

In all of the foregoing conventional designs, it is necessary for the operator to impart a rubbing motion of the blade member over the skin, and a given surface of the skin must be traversed repeatedly in order to obtain a close and satisfactory shave. A single pass of the cutter member over the skin will only partially cut the hair, because it is impossible for all of the hair, in one pass of the cutter member, to enter the spaced openings. This necessity of repeatedly traversing the blade over the same surface of the skin, has been one of the most serious handicaps of the electrical razor.

It is an object of the present invention to provide an electrical shaving device which will overcome the disadvantage pointed out above, and which will make possible rapid and efficient dry shaving.

Further objects of the invention will appear from the following description in which the preferred embodiments of the invention have been set forth in detail in conjunction with the accompanying drawing.

Referring to the drawing:

Fig. 1 is a side elevational view, illustrating an electrical shaver incorporating the present invention.

Fig. 2 is an enlarged cross-sectional detail of the device shown in Fig. 1.

Fig. 3 is a cross-sectional detail taken along the line 3—3 of Fig. 2.

Fig. 4 is a cross-sectional detail taken along the line 4—4 of Fig. 3.

Fig. 5 is an enlarged cross-sectional detail, showing another embodiment of the invention in which the cutter both reciprocates and oscillates.

Fig. 6 is a cross-sectional view similar to Fig. 2, showing another embodiment in which the cutter reciprocates with respect to the blade member.

Fig. 7 is a cross-sectional view similar to Fig. 2 showing a further embodiment in which compound cyclic movement is imparted to the blade member.

Referring to that form of the invention illustrated in Figs. 1 to 4, inclusive, it consists of a handle 10, made of some suitable material like a molded plastic, and serving to house an electric motor 11. Secured to one end of this handle there is a cutting mechanism including the blade member 12 and the cutter 13. In this instance the blade member 12 is curved or semi-cylindrical in form, and is provided with a plurality of spaced openings 14 to receive hair. The cutter 13 is slidably held by a retaining arm 16, which in turn is secured to rocker shaft 17. A compression spring 18 is shown for resiliently urging the outer edge of cutter 13, against the inner periphery of blade member 12.

10 The blade member 12 is secured to the outer end of a mounting head 19. This mounting can be formed of some suitable metal, and it consists in this instance of the parallel side walls 21, secured to the inner end wall 22. Side walls 21 carry suitable trunnions or bearings 23, for the rocker shaft 17. It will be noted that the casing 10 is provided with a recess 24 of ample proportions, to accommodate the mounting 19. Members 20 are pivotally carried by the walls 21, and 15 serve to releasably retain the blade member 12 in place.

20 The electric motor 11 is equipped with the rotatable shaft 25. This shaft is shown extending through a bearing sleeve 26, and its projecting end has certain drive connections to both the cutter and the mounting 19, as will be presently explained. Surrounding the sleeve 26 and fixed within the handle, there is a block 27.

25 The attachment between the mounting 19 and block 27 is such as to enable a substantial amplitude of movement of the head 19 relative to the handle. A suitable form of connection which will serve this purpose is illustrated in Fig. 4. In this instance a plate 28 is attached to the lower end wall 22 of the mounting 19, as by means of screws 29. Both block 27 and plate 28 have openings 31 and 32, which loosely accommodate the retention pins 33. The upper ends of the pins 33 have enlarged heads 34, and their lower ends 30 are surrounded by the compression springs 36. The lower end of each spring seats upon a thrust washer 37, while the upper end of each spring 35 engages the adjacent portion of the block 27, whereby each spring exerts a force tending to retain plate 28 in contact with the block 27, with-

out however interfering with sliding movement of the plate 28 over the surface of block 27.

The drive connections to the end of shaft 25 are such as to cause movement of the cutter 13 relative to the blade member, and simultaneously cause cyclic movement of the blade member and its mounting 19, relative to the handle. Cyclic movement in this instance is in a substantially circular orbit, although the movement may be varied or modified in different instances. Thus to form the drive connection to the cutter 13, the rocker shaft 17 carries a crank arm 41, the end of which carries a pivoted trunnion 43. This trunnion is engaged by a roller 44, which in turn is carried eccentrically by the adjacent end of shaft 25.

To form the other second drive connection, the shaft 25 carries an eccentric 46, which engages within the annular opening 47 afforded in the plate 28. Thus as the shaft 25 rotates, plate 28, together with the head mounting 19 and the blade member 12, is moved in a circular orbit the diameter of which equals the total throw of the eccentric 46. Such a circular orbit is permitted by virtue of the type of connection between the plate 28 and block 27, and at the same time this connection prevents relative rotation between the plate 28 and block 27.

As pointed out above when the device is in operation the cutter 13 moves across the underside of the blade member 12, and at the same time the blade member is moved in a substantially circular orbit at a relatively rapid rate. The amplitude of this circular orbit, that is the amplitude of the cyclic movement imparted by the additional drive connection to the motor shaft, may vary in different instances, although it is preferably substantially greater than the width of the openings 14. In the proportions illustrated the amplitude of the cyclic movement is as great as the total span of two adjacent openings, in order to afford utmost opportunity for hair to enter the openings. Assumed a speed of operation of the motor such as is commonly used with electrical razors, as the blade member 12 is contacted with the skin and moved along a given path, the cyclic movement imparted to the blade member causes rapid relative movement of the blade member with respect to the skin, and this movement occurs at such a rate that all of the hair in the path of movement is given ample opportunity to enter the openings 14. As a result my device can make a substantially complete cutting of all hairs along a certain path of movement of the cutter member. Thus repeated traversing over the same surface is not essential, as with prior electrical shavers, with the result that a shaving operation is greatly simplified and facilitated. In addition the cyclic movement imparted to the blade member as it engages the skin tends to afford a closer shave, presumably because of the action of the blade member in cyclically moving at a rapid rate against the surface of the skin.

In the foregoing it should be understood that some vibration is necessarily imparted to the handle of the device, because of the rapid cyclic movement imparted to the operating head. Such vibration of the handle is not objectionable of itself, and it is not of serious intensity because of the relatively larger weight of the handle and the motor, compared to the weight of the operating head. In this connection it can be noted that lightness of weight of the operating head,

also tends to decrease the intensity of vibration imparted to the handle.

Fig. 5 illustrates another form of the invention in which the cutter is of cylindrical form and both oscillates and reciprocates. The blade member 51 in this instance is provided with tapered cutting teeth 52, and encloses the cylindrical cutter 53. The cutter also has spaced cutting blades 54, to cooperate with the blades 52. The end of the motor shaft 55 is shown provided with an eccentric 56, which engages the annular bearing 56, afforded in the base 57 of cutter 51. The cutter base 57 is also retained to the handle of the device by some form of attaching means such as illustrated in Fig. 4, whereby the cutter may move a limited amount relative to the handle. An eccentric roller 58 forms an operative connection between eccentric 56 and the cutter 53, whereby the cutter is oscillated and simultaneously reciprocated with respect to the blade member 51.

The operation of that form illustrated in Fig. 5 is substantially the same as the form previously described. The blade member is moved cyclically relative to the handle at a rapid rate simultaneously with movement of the cutter relative to the blade member.

Fig. 6 illustrates another form of my invention in which the cutter reciprocates relative to the outer blade member. Thus in this instance the blade member 61 is substantially U-shaped and it is provided with a plurality of laterally extending slots to form the relatively thin flat blade portions 62. The cutter 63 fits within the blade member 61, and it is likewise slotted to afford a series of spaced cutter blades 64, to cooperate with the plate portion 62. The base 66 of the cutter member 61 is attached to the handle 67 of the device, by some form of attachment enabling relative movement between these parts, as has been previously described with reference to Fig. 4. The motor shaft 68 carries an eccentric 69 which is journaled within the base portion 66. Also eccentric 69 carries a pin 71, which is eccentric with respect to the center of shaft 68, and which engages within a laterally extending slot 72, formed in the base of the cutter 63. Thus in Fig. 6, as the shaft of the motor is driven, the entire operating head is moved in a substantially circular orbit, while at the same time the inner cutter is reciprocated relative to the outer blade member. Otherwise the operation of this form of the invention is substantially the same as with the device of Figs. 1 to 4 inclusive.

Another embodiment is shown in Fig. 7 in which a compound cyclic movement is imparted to the blade member. In this case the blade member 12 and cutter 13, and associated parts, are shown substantially the same as in Fig. 2. However, in place of the simple eccentric 46 of Fig. 2, I employ an eccentric 46a which has its end surface 46b at an angle to the axis of rotation to afford a wash plate effect. Plate 28 is also provided with an annular shoulder 74 which is at an angle to the lower face of block 28 and which cooperates with cam surface 46b. When the device of Fig. 7 is in operation, engagement of surfaces 46b and 74 causes cyclic movement of the plate 28 toward and away from the block 27, and consequently the blade member 12 is vibrated against the skin, in addition to cyclic movement along the surface of the skin. Vibrating movement against the skin has been found desirable in that it affords a closer shave and in addition

it facilitates cyclic movement of the blade along the surface of the skin.

I claim:

1. In an electrical shaver, an outer blade member adapted to contact the skin and having openings to receive hair, a cutter cooperating with one side of the blade member and serving to cut hair received in said openings, a handle to which both the blade member and the cutter are secured, an electrical motor carried within the handle, said motor being provided with a rotatable shaft, means forming a drive connection between the shaft of the motor and the cutter to move the cutter relative to the blade member, and means forming a positive drive connection between the shaft and the blade member serving to gyrate the blade member relative to the handle simultaneously with relative movement between the cutter and the blade member.

2. In an electrical shaver, an outer blade member adapted to contact the skin and having openings to receive hair, a cutter-cooperating with the blade member and serving to cut hair received in said openings, a handle to which both the blade member and the cutter are secured, an electrical motor carried within the handle and provided with a rotatable shaft, means forming a drive connection between one end of the shaft and the cutter whereby the cutter is moved by the motor relative to the blade member, and means forming a positive eccentric drive connection between the motor shaft and the blade member to gyrate the blade member relative to the handle and the skin.

3. In an electrical razor, an outer blade member adapted to contact the skin and having open-

ings to receive hair, a cutter cooperating with the blade member and serving to cut hair received in said openings, a handle, electrical motor means carried by the handle, means forming a drive connection between said motor and the cutter to drive the cutter relative to the blade member, and means forming a drive connection between the motor and the blade member to cause gyratory movement of the blade member relative to the handle, the amplitude of said movement being at least as great as the width of said openings.

4. In an electrical shaver, an outer blade member adapted to contact the skin and having openings to receive hair, a cutter cooperating with the blade member and serving to cut hair received in said openings, means for causing movement of the cutter relative to the blade member, and means for imparting compound recurrent movement to the blade member, whereby the blade member is vibrated against the skin and gyrated at a rapid rate over the surface of the skin.

5. In a shaving device, the combination of a handle, a thin, apertured, convex, skin-contacting shear plate movably mounted on said handle, a movable inner cutter having at least one shearing edge curved complementarily to and bearing against the concave under surface of said plate, and means for moving said plate and said cutter relatively to each other and to said handle to sever hairs projected through the apertures in said shear plate said means comprising a shaft and means eccentric to the shaft for gyrating the shear plate.

RALPH D. S. HAGOPIAN.
